STARTING AND OPERATING DEVICES AND
CIRCUITS FOR ELECTRIC DISCHARGE DE-
VICESPhilippe Waguet, Paris, France, assignor to Gen-
eral Electric Company, a corporation of New
YorkApplication June 16, 1948, Serial No. 33,386
In France June 14, 1947

2 Claims. (Cl. 315—165)

1

This invention relates to electric discharge devices of the type employing ionizable mediums such as gases or vapors, and more particularly to starting and operating devices and circuits therefor.

An object of my invention is to provide a new and improved starting and operating circuit for electric discharge devices energized from a direct current source.

Another object of my invention is to provide an improved and simplified operating circuit for luminous electric discharge devices or fluorescent lamps energized in series from a direct current source, and utilizing an auxiliary dependent alternating voltage source for heating the electrodes and starting the discharge in the lamps.

My invention is of general applicability whenever it is desired to operate fluorescent lamps from a direct current supply. It has been found particularly useful in the illumination of cars on electrified railways and permits the immediate utilization of the direct current supplied to the locomotive, for instance the traction supply at 750 or 1500 volts, on the lighting circuits.

A feature of my invention is the utilization of an auxiliary direct-to-alternating current converter for heating the filamentary electrodes in the lamp and also for starting the discharge. This is achieved by means of a time-delay relay which permits the utilization of the induced voltage, resulting from the rupture of the field winding circuit of the converter, as a starting impulse for the lamps.

For a more complete discussion of various circuits which may be utilized in operating fluorescent lamps from a direct current supply, reference is made to my copending U. S. application No. 28,223, filed May 20, 1948. Other applications and improvements in such circuits are disclosed in my copending U. S. applications Nos. 28,224, 28,225 and 28,226, filed May 20, 1948, and 33,385 and 33,387, filed June 16, 1948. All of the above applications are assigned to the same assignee as the present application.

For a better understanding of my invention, reference may be had to the following description taken in connection with the accompanying drawing and its scope will be pointed out in the appended claims. The drawing is a diagrammatic view of a plurality of electric discharge devices connected in series and a starting and operating device and circuit therefor incorporating my invention.

Referring to the drawing, I have there illustrated one embodiment of my invention as applied to a group of two or more serially connected

2

electric discharge devices wherein the reference numerals for device 1a and the elements associated with device 1a are extended by indices to the other serially connected device or devices.

5 The electric discharge device 1a (and 1b), such as a fluorescent lamp, therein illustrated comprises an elongated tubular or cylindrical envelope 2a having sealed into the ends thereof thermionic filamentary electrodes 3a and 4a. 10 Filamentary electrodes 3a and 4a may comprise a coil, preferably in the form of a coiled coil of tungsten wire activated with oxides of alkaline earth metals such as a mixture of barium and strontium oxides. The envelope 2a contains a 15 gaseous atmosphere such as a rare gas like neon, argon or mixtures thereof at a pressure of a few millimeters and a small quantity of mercury which, during the operation of the lamp, has a low pressure of the order of 10 microns. The 20 device 1a may be a low pressure positive column lamp of a fluorescent type provided with a suitable phosphor or fluorescent coating. This fluorescent coating, upon excitation by the radiation produced by an electric discharge between the electrodes, transforms a shorter wave radiation due to the discharge into longer wave radiation such as radiation within the visible range. A pair of metal cups 5a and 6a serve to intercept the particles of emissive material sputtered from 25 electrodes 3a and 4a, respectively. These cups are usually tied by means of connections, either outside or inside of the lamp, to the extremities of electrodes 3a and 4a. A number of advantages result from the connections between filamentary electrodes 3a and 4a and the corresponding cups 30 5a and 6a, namely, utilization of cup 6a as an anode and eliminating the disintegration by ionic bombardment of filamentary electrode 4a, utilization of lamps that are usually employed with alternating current, reduction of operating voltage, doubling the life of the lamp by using successively the two filamentary electrodes, i. e., by turning the lamps around when one of the filaments becomes inoperative.

45 Serially connected devices 1a and 1b are connected across a suitable direct current power supply 1,1' which, for example, may be a traction voltage of either 750 or 1500 volts, and in series with an auxiliary or second direct current source of supply 8 which, for example, may be a storage 50 battery having a potential of 72 volts and connected in series with the devices 1a and 1b in such a manner that it will be charged by the current passing through the devices. The direct current source of supply 1,1' supplies current to devices 1a and 1b through stabilizing resistances 55

9a and 9b. Resistances 9a and 9b, for example, may be iron or tungsten wire enclosed in hydrogen. A starting and operating circuit 10, 10' is connected across the auxiliary direct current supply 8 and comprises in series relationship a field winding section 11 of a dynamoelectric machine or rotary converter 12, a manual make-and-break switch 13, and a switching means 14 comprising a normally closed contactor 15 and a normally open contactor 16. Auxiliary electrodes 17a and 17b, mounted adjacent devices 1a and 1b, respectively, are connected to a common point 18 intermediate field winding section 11 and contactors 15 and 16 of switching means 14. The time-delay relay or switching means 14 comprises a coil 19 connected across the terminals of the direct current source of supply 7, 7'. Switching means 14, in addition, comprises a normally closed contactor 20 and a normally open contactor 21 in series with each other and with an armature winding 22 of dynamoelectric machine 12 and switch 13 across the auxiliary source of direct current supply 8. A time-delay relay or switching means 23 comprising a contactor 24 in series with the direct current source of supply 7, 7', and a coil 25 connected across the auxiliary source of direct current supply 8, energizes the starting and operating circuits for devices 1a and 1b upon closure of switch 13.

Transformers 26a and 26b comprising primary winding sections 27a and 27b and center-tapped secondary winding sections 28a and 28b, respectively, are connected in parallel across an alternating current supply 29, 29' produced by the dynamoelectric machine 12. The secondary winding sections 28a and 28b serve to heat filamentary electrodes 4a and 4b and to continue to heat these electrodes as long as primary winding sections 27a and 27b are energized. The center-tap of the secondary winding section 28b is connected through the ballasting resistance 9a to the filamentary electrode 3a of device 1a, and the center-tap of the secondary winding section 28a is connected through the auxiliary source of direct current supply 8 to the negative terminal 7 of the direct current supply.

The operation of the circuit and device illustrated in the drawing is as follows: In the rest position, as shown in the drawing, the contactors 16 and 21 are open and the contactors 15 and 20 are closed. As soon as the starting switch 13 is closed, coil 25 of the feeder relay 23 is energized, the contactor 24 closes and applies the network voltage to coil 19 of relay or switching means 14, as well as to all the lamps that are connected in series. Contactor 16 closes and applies voltage to field winding section 11; then contactor 21 closes, with a time delay of a few tenths of a second with respect to the closing of contactor 16, and applies voltage to the armature winding section 22 of the converter or dynamoelectric machine 12, which now starts to operate. The cathode filamentary electrodes 4a and 4b are heated and after a few seconds the contactor 20 opens, interrupts the circuit of armature winding section 22 and stops the heating of the cathode filamentary electrodes. A few tenths of a second after the opening of contactor 20, contactor 15 opens and breaks the circuit of field winding section 11, thus setting up at point 18 a voltage impulse which is imparted to the auxiliary electrodes 17a and 17b. As a result of this impulse the discharge lamps 1a and 1b light up. In case the system voltage should fail, relay or switching means 14 will immediately assume the rest posi-

tion, the contactors 15 and 20 close, contactors 16 and 21 open, and the armature and field circuits of the converter or dynamoelectric machine are interrupted. Upon re-establishment of the normal system voltage, the switching means 14 again operates as just described, so that the lamps are re-ignited in their entirety. Switching means 14 is so adjusted that it will not drop to the rest position unless the system voltage falls to a value slightly above the voltage at which the series connected lamps will go out. Should the system voltage fall below that value, switching means 14 drops to the rest position, just as in the case of no voltage.

It is evident that the circuit, which has been just described for the case of a group of lamps that are connected in series, is also applicable to any number of these series groups which are connected in parallel.

The retarded operation of contactors 15, 16, 20, and 21 of switching means 14 may be brought about, for instance, by means of a mechanism set in motion by the coil 19 which causes the tilting of two glass bulbs containing mercury, the flow of which, suitably delayed by a capillary tube, serves to make or break the contact.

Other means for carrying out this function, such as mechanical timing devices for instance, will occur to those skilled in the art. The appended claims are, therefore, intended to cover any such modifications coming within the true spirit and scope of the invention.

What I claim as new and desire to secure by Letters Patent of the United States is:

1. Apparatus for operating a plurality of gaseous luminous electric discharge devices, of the type including a main thermionic electrode and a co-operating electrode, comprising: said devices, a unidirectional voltage source, and a ballast resistance; a rotary converter having a direct current field winding, a direct current input winding and an alternating current output winding; a transformer having a primary winding connected to said output winding and a plurality of secondary windings connected to said thermionic electrodes; a main discharge circuit constituted by connecting said devices in series, the thermionic electrode of one being connected to the co-operating electrode of another in sequence, the two remaining main electrodes being connected, in series with said ballast resistance, across said source; a time delay relay having two sets of contacts respectively connecting said field and said input windings across said source, said relay operating to energize in sequence, first said field winding and then said input winding, and said relay then operating to de-energize in sequence after a predetermined time interval, first said input winding and then said field winding; and auxiliary starting electrodes on said devices connected in common to the junction of said field winding with the associated contact of said relay.

2. Apparatus for operating a plurality of gaseous luminous electric discharge devices, of the type including a main filamentary thermionic electrode and a co-operating main electrode, and an auxiliary starting electrode located intermediate the ends thereof, comprising: said devices, a unidirectional voltage source, and a ballast resistance; rotary converter having a direct current field winding, a direct current input circuit and an alternating current output circuit; a transformer having a primary winding connected to said output circuit and a plurality of secondary windings connected to said filamentary electrodes;

a main discharge circuit constituted by connecting said devices in series, the filamentary electrode of one being connected to the cooperating electrode of another in sequence, the two remaining main electrodes being connected, in series with said ballast resistance, across said source; and a time delay relay having two sets of contacts respectively connecting said field winding and said input circuit across said source, said relay operating to energize in sequence, first said field winding and then said input circuit, and said relay then operating to de-energize in sequence, after a predetermined time interval sufficient to permit heating of said filamentary electrodes, first said input circuit and then said field winding; 15 and direct connection between said auxiliary starting electrodes and the junction of said field winding with the associated contact of said relay.
